United States Patent Office

Des. 180,062

Patented Apr. 16, 1957

180,062

VIBRATORY TOOL

Warren C. Burgess, Jr., North Olmsted, Ohio

Application July 13, 1954, Serial No. 31,410

Term of patent 14 years

(Cl. D54—14)

Fig. 1

Fig. 2

Fig. 3

Fig. 4

Fig. 1 is a perspective view of a vibratory tool showing my new design;

Fig. 2 is a side elevational view of the tool;

Fig. 3 is an end elevational view of the tool; and

Fig. 4 is a top view of the tool.

The essential features of my design reside in the portions shown in full lines.

I claim:

The ornamental design for a vibratory tool, substantially as shown and described.
